Primary Examiner — Ian Simmons*Assistant Examiner* — Richelle G Shelton(74) *Attorney, Agent, or Firm* — Lihua Zheng; Proskauer Rose LLP(57) **CLAIM**

We claim the ornamental design for a nasal delivery device, as shown and described.

DESCRIPTION

FIG. 1 illustrates a perspective view of the nasal delivery device;

FIG. 2 illustrates one side view of the nasal delivery device; FIG. 3 illustrates the other side view of the nasal delivery device;

FIG. 4 illustrates a front view of the nasal delivery device; FIG. 5 illustrates a rear view of the nasal delivery device; FIG. 6 illustrates a plan view of the nasal delivery device; and, FIG. 7 illustrates an underneath plan view of the nasal delivery device.

The broken line showing is included for the purpose of illustrating environmental structure with the line itself and all within forming no part of the claimed design.

1 Claim, 6 Drawing Sheets(56)
